(57) **CLAIM**

The ornamental design for a tire sidewall, as shown and described.

DESCRIPTION

FIG. 1 is a perspective view of a tire sidewall showing our new design;

FIG. 2 is a front elevational view thereof; and,

FIG. 3 is an enlarged fragmentary perspective view taken from FIG. 1 thereof.

In the drawings, the broken lines showing of the tire tread, inner bead and the peripheral boundary between the tire tread and the sidewall in FIGS. 1 through 3 depict environmental subject matter and form no part of the claimed design. The dashed broken lines indicating an enlargement portion of the design form no part of the claimed design.
